INVENTOR

UNITED STATES PATENT OFFICE

112,580

DESIGN FOR A NECKTIE FASTENER OR SIMILAR ARTICLE

Charles Silverman, Providence, R. I.

Application August 24, 1938, Serial No. 79,547

Term of patent 3½ years

To all whom it may concern:

Be it known that I, Charles Silverman, a citizen of the United States, residing at Providence, in the county of Providence and State of Rhode Island, have invented a new, original, and ornamental Design for a Necktie Fastener or Similar Article, of which the following is a specification, reference being had to the accompanying drawing, forming part thereof.

I claim:

The ornamental design for a necktie fastener or similar article, as shown.

CHARLES SILVERMAN.
